UNITED STATES PATENT OFFICE.

CHARLES W. GLIDDEN, OF LYNN, ASSIGNOR TO JAMES W. BROOKS,
TRUSTEE, OF CAMBRIDGE, MASSACHUSETTS.

HEEL-TRIMMING MACHINE.

SPECIFICATION forming part of Letters Patent No. 393,103, dated November 20, 1888.

Application filed May 28, 1888. Serial No. 275,362. (No model.)

To all whom it may concern.

Be it known that I, CHARLES W. GLIDDEN, of Lynn, county of Essex, State of Massachusetts, have invented an Improvement in Heel-Trimming Tools, of which the following description, in connection with the accompanying drawings, is a specification, like letters on the drawings representing like parts.

This invention is an improvement on that class of tools having a series of blades pivoted at their inner ends and co-operating with a rand-guide having a lip or flange to arrest the outer ends of the blades, so that their cutting-edges face in the same circle, my present invention being an improvement upon that described in application Serial No. 268,851, filed March 29, 1888, wherein the pins or pivots about which the heels of the blades turn are so held in the hub as to always occupy a position at the same distance from the center of rotation of the cutting-tool. Blades of this kind when made are shaped externally to give to them such curvature as shall afford just the right amount of "clearance."

The blades referred to in use become dulled and are frequently ground, each grinding shortening the blades, so that when again applied to the tool the blades occupy each time a more nearly radial position, and with each shortening of the blades by grinding the clearance is also altered by reason of the different angle assumed by the blades. It is a great desideratum to maintain the clearance the same under all conditions, and to do this I have mounted the near or inner ends of the blades or pivots, which are made movable toward and from the center of rotation of the tool, so that as the blades are shortened by grinding the pivots on which the blades turn may be moved away from the said center sufficiently to compensate for the shortening of the blades.

My invention in rotary tools for trimming heels consists, essentially, in a hub and a rand-guide having a lip to arrest the outward movement of the free ends of the blades, combined with pivots for the said blades, which are made movable away from the center of rotation of the tool as the blades are shortened by grinding, to thus maintain the clearance of the blades uniform.

Figure 1 represents one of my improved

tools with the rand-guard removed. Fig. 2 shows the inner side of the rand-guard removed from Fig. 1. Fig. 3 shows the entire tool in section on the line *x*, Fig. 1; and Fig. 55 4, a diagram to illustrate my invention.

The shaft *A*—common to any heel-trimming machine—has mounted upon it a tread-guard, *B*, of usual construction. The shaft *A*, as shown, has two many-sided or other than cylindrical holding-surfaces, *a b*, which receive upon them, respectively, the pivot-holding plate *c* and the rand-guide *d*, the plate *c* and rand-guide at their contiguous faces having respectively, as shown, three eccentric slots, 2 and 3. The holding-surfaces *a b* compel the parts *c* and *d* to rotate in unison with the shaft *A*.

The cylindrical portion *e* of the shaft *A*, between the holding-surfaces *a b*, receives upon it the hub or head *f*, having slots, as best shown in Fig. 1, which slots receive the pins or pivots *g*, on which turn freely the inner ends of the blades *h*, the outer or free ends of which when the tool is in operation rest against the lip or flange *i* of the rand-guide.

In Fig. 1 the blades are supposed to be of full length, and the pins or pivots *g* bottom in the slots of the hub, and the arcs in which lie the backs *k* of the blades afford the proper amount of clearance. Now, as the blades are shortened by grinding, they, if the pins or pivots *g* were always held at the same distance from the center of the shaft, would eventually assume a position such as shown by the shortened blade, full lines, Fig. 4, when the clearance would be very different from that shown in Fig. 1. To overcome this the ends of the pins or pivots *g* enter the eccentric slots or cam-surfaces 2 and 3, and when the blades are ground back and shortened the operator will change the relative position of the hub and shaft by holding one and turning the other slightly, which will cause the eccentric slots 2 and 3 to move the pins or pivots *g* out away from the center of rotation of the shaft *A*, thus keeping the clearance substantially the same under all changing conditions of the blades.

The dotted lines, Fig. 4, show the shortened blade carried out at its pivoted end to maintain the clearance to the standard.

The washer *m* and nut *n* keep the rand-

guide, hub, and plate *c* on the shaft and clamp them together with such force that one cannot be rotated independently of the other except by loosening the nut.

5 I claim—

The shaft *A*, the slotted plate *c*, and the rand or counter guard *d*, the latter slotted at 3 at its inner side, and provided with a lip, 4, combined with the hub *f*, the blades 5, pivoted at their 10 heels upon pins *g*, resting in slots of the hub, the said pins entering the slots in the plate *c*

and in the slots 3 of the rand or counter guard, and a tread-guard, the combination being and operating substantially as described.

In testimony whereof I have signed my name 15 to this specification in the presence of two subscribing witnesses.

CHARLES W. GLIDDEN.
